C. E. HELLMAN

CAVITY DRILL

Filed May 26, 1923

Inventor
C. E. Hellman.

By *Albemarle, Jr.* Attorney

UNITED STATES PATENT OFFICE.

CHARLES E. HELLMAN, OF EAGLE PASS, TEXAS.

CAVITY DRILL.

Application filed May 26, 1923. Serial No. 641,638.

To all whom it may concern:

Be it known that I, CHARLES E. HELLMAN, a citizen of Finland, residing at Eagle Pass, in the county of Maverick and State of

6 Texas, have invented certain new and useful Improvements in Cavity Drills; and I do hereby declare the following to be a full, clear, and exact description of the invention, such as will enable others skilled in the art 10 to which it appertains to make and use the same.

The invention has for its object the provision of a drill bit for mining and tunneling operations, whereby the opening may be 15 enlarged at the bottom to permit a greater area for the placing of an explosive where it will do the best work and develop a greater force by a less amount of explosive than by the old method.

20 A further purpose of the invention is the provision of a drill bit for finishing the opening which is enlarged, thereby making it possible to concentrate the explosive at the bottom of the opening and thereby rendering the same more effective.

Other objects and advantages will be apparent and suggest themselves as the nature of the invention is understood.

25 While the drawings illustrate an embodiment of the invention it is to be understood that in adapting the same to meet different conditions and requirements, various changes in the form, proportion and minor details of construction may be resorted to 30 without departing from the nature of the invention.

Referring to the accompanying drawings forming a part of the application:

Figure 1 is a front edge view of a drill 40 bit embodying the invention.

Figure 2 is a side view of the bit looking at it from the left side of Figure 1, and

Figure 3 an end view thereof.

45 Corresponding and like parts are referred to in the following description and designated in the several views of the drawings by like reference characters.

The numeral 1 designates the drill bit 50 which is made of the same material as other bits and is designed to be used as a finish bit for enlarging the lower end of the open-

ing. The bit consists of a flat bar and its active or cutting end is extended laterally at one side only, as indicated at 2. The opposite or rear edge 3 of the bit is straight. 55 The lower end of the bit is inclined throughout its length, as indicated at 4, and is beveled from opposite sides to a cutting edge. The lateral extension 2 is likewise beveled from opposite sides to a cutting 60 edge, as indicated most clearly in Figure 3. The passageway 5 extending through the bit is deflected laterally at the lower end, as indicated most clearly in Figure 1. This passageway is adapted for the forcing of 65 water through it to expunge mud or cuttings and also to minimize heating of the bit. The lower cutting edge 4 inclines forwardly and downwardly from the rear edge 3 and intersects with the forward cutting 70 edge of the lateral extension 2. The rear edge 3 is transversely curved, as indicated most clearly in Figure 3. The bit is operated in the well known manner, being reciprocated and rotated and at each downward 75 movement of the bit, the inclined edge 4 glancing on the bottom of the opening results in a lateral movement of the bit whereby the cutting edge of the lateral extension 2 operates laterally on the side wall of the 80 opening, thereby enlarging the same with the result that the bottom of the opening is enlarged to receive the explosive which is confined by the portion overhanging the enlargement with the result that the explosion of the charge results in greater execution than ordinarily.

85 What is claimed is:

1. A bit having a lateral extension at its lower end and having the latter inclined 90 forwardly and downwardly from the rear edge of the bit and intersecting with the forward cutting edge of the lateral extension, both the lower end of the bit and the outer edge of the lateral extension being 95 beveled from opposite sides and throughout their length to form cutting edges.

2. A bit of the character specified having its rear edge straight and transversely 100 curved, and having a lateral extension at its lower end and having the latter inclined forwardly and downwardly from the rear edge

2
and intersecting the outer edge of the lateral extension, both the lower end of the bit and the outer edge of the lateral extension being beveled from opposite sides and throughout their length to form cutting edges, and said bit having a water passage therein which is deflected at the outlet 1 at-

erally to one side of the lower cutting edge.

In testimony whereof I affix my signature in presence of two witnesses.

CHARLES E. HELLMAN.

Witnesses:

H. P. MATHIS,

A. B. BOUBEL.
